UNITED STATES PATENT OFFICE.

WILLIAM L. GROUT AND EDWARD L. BOWERS, OF ORANGE, MASSACHUSETTS.

MECHANICAL MOVEMENT.

SPECIFICATION forming part of Letters Patent No. 373,525, dated November 22, 1887.

Application filed August 15, 1887. Serial No. 247,002. (No model.)

To all whom it may concern:

Be it known that we, WILLIAM L. GROUT and EDWARD L. BOWERS, both of Orange, county of Franklin, State of Massachusetts, 5 have invented an Improvement in Mechanical Movements, of which the following description, in connection with the accompanying drawings, is a specification, like letters on the drawings representing like parts.

10 This invention has for its object the production of novel mechanism by which a connecting-rod driven by a crank or eccentric rotates three or more parallel shafts.

15 Our invention is especially applicable in sewing-machines, but may be used in any class of machine wherein it is desired to rotate three or more parallel shafts by one connecting-rod.

20 Figure 1 shows our invention embodied in connection with a sewing-machine, and Fig. 2 a section of Fig. 1 on the line *x*, looking to the left.

25 The bed-plate *A* and overhanging arm *A'* are and may be as in any usual sewing-machine. The upright portion of the arm is provided with a crank-shaft, *B*, on which is secured a driving-pulley, *D*. The crank of the shaft *B* has mounted upon it and supports a connecting-rod, *E*, having a right-angled extension, *E'*, the said connecting-rod and its extension having a series of half-boxes, *a b c*, (see Fig. 2,) with which co-operate other half-

35 boxes, *a' b' c'*, the said boxes embracing crank-pins *a' b' c'* on the disks attached to the shafts *a' b' c'*, all parallel and driving, it may be, respectively, the needle-bar, the lower thread-carrier, and the feeding devices. The rotation of the shaft *B* actuates the connecting-rod, and it rotates all the said shafts at the same speed and in the same direction.

40 We are aware that heretofore two parallel shafts have been driven by a third shaft by using one or more connecting-rods, as in the patent to Rowell, No. 64,450, dated May 7,

1867, and such a device is not broadly claimed 45 by us; but, prior to our invention, we are not aware that three parallel shafts have been driven by a fourth shaft, by one connecting-rod, as herein shown.

50 We claim—

55 The cranked driving-shaft and the parallel shafts *a' b' c'*, combined with a connecting-rod joined to and rotating the said shafts in the same direction in unison, substantially as described.

55 In testimony whereof we have signed our names to this specification in the presence of two subscribing witnesses.

WM. L. GROUT.
EDWARD L. BOWERS.

Witnesses:

H. S. DAWLEY,
EDWARD WHITNEY.
